UNITED STATES PATENT OFFICE.

ALFRED CASTANIEN, OF COLUMBUS, OHIO.

COMBINED TABLE AND TUB.

Application filed May 5, 1927. Serial No. 189,141.

In rural as well as in other districts where modern domestic conveniences and services are not available or where rooms are few or small, furniture and other household equipment must be compact. The particular object of the present invention is to provide a combined tub and table, the tub being readily available either for bathing or laundry purposes.

10 The invention is embodied in the example herein shown and described the features of novelty being finally claimed.

Figure 1 is a front elevation of the invention with parts omitted and showing the tub 15 in extended position.

Fig. 2 is an end elevation of the same with parts omitted and in section.

Fig. 3 is a view similar to Fig. 2 showing the tub shoved under the table and elevated.

20 Fig. 4 is a detail partly in section showing one of the rollers for supporting the tub on one of the tracks.

Fig. 5 is a detail in edge view of the rear link for sustaining the inner track at its inner end in elevated position.

As shown in the views the table is of the ordinary kitchen variety except that it has a top 6 hinged at 7 to one of the longer edges of the top frame 8 of the table.

30 The tub, designated 9, is equipped at each of its ends with a pair of rollers 10 mounted on brackets 11 secured to the tub. The tub has a vent at 9^a to drain water from the tub, said vent to be provided with a suitable stopper. The vent can have a threaded connection for a hose to carry away the water. The tub travels on a pair of rails, each including an inner short portion 12 and an outer longer portion 13 hinged together as 35 at 14. The said portions of rail are shown as formed of channel bar they being hinged together so that their ends shall substantially abut to make a continuous rail when alined as in Fig. 2. The inner end of a

40 rail part 12 is connected by a link 15 to a cross bar 16 secured between each of the pairs of end legs of the table, said link being hinged at 17 to the rail portion and hinged at 18 to the cross bar. Said link 15 is preferably double as shown in detail in Fig. 5 to make it strong and steady because it supports the tub and laundry water when the tub is in elevated position as shown in Fig. 3.

45 Each of the longer track portions 13 has hinged to its outer end at 19 a leg 20 to

support said track portion when extended and alined with the short track portion 12 as best seen in Fig. 2. The longer track portion 13 is pivoted at 21 to the adjacent forward leg.

The shorter track portion 12 has a stop 22 to limit the rearward movement of the tub, while the longer track portion 13 has a stop 23 to limit the forward movement of the tub.

50 The leg 20 can be folded up against the longer track portion and retained in position parallel the leg by lugs 24 and 25, the leg being adapted to spring past the outer 55 of said lugs into place between the lugs.

The rails and their appurtenances at each end of the table are symmetrical duplicates.

55 The four hinging points 14, 17, 18 and 21 are substantially at the corners of a parallelogram so that by raising the outer track portions 13 the inner track portion 12 can be lowered to aline said portions and the tub then drawn out onto said track portion 13 for bathing purposes as shown in Fig. 2; and conversely by lowering and pressing down said track portions 13 (after the tub has been shoved in) the inner rail portions and the tub thereon will be elevated as shown in Fig. 3. In this last described position the tub can be used for doing the laundry work at which time an ordinary toggle brace 26 connecting the table top and frame is used, when the toggle is straightened by raising the table top sufficiently, to hold the 60 table top up to afford access to the tub.

65 It will be observed, therefore, that with my invention the tub when not used for bathing or laundering purposes is entirely out of the way, and when not thus used is substantially concealed. Because the tub and table are separable either can be independently repaired or replaced or crated for transportation.

70 The forms of the parts can be changed without departing from the gist of the invention as claimed.

What I claim is:

75 1. In combination with a table, rails for supporting a tub movably mounted below the top of the table, supplementing rail extensions connected with the first mentioned rails, said last named rails fulcrumed to raise and lower the first mentioned rails.

80 2. In combination with a table, rails for supporting a tub movably mounted below the top of the table, supplementing rail ex-

tensions connected with the first mentioned rails, said last named rails fulcrumed on fixed points to raise and lower the first mentioned rails.

5. 3. In combination with a table, rails for supporting a tub movably mounted below the top of the table, supplementing rail extensions connected with the first mentioned rails, said last named rails fulcrumed to raise 10 and lower the first mentioned rails, and a tub to travel on all said rails.

4. In combination with a table, a pair of rails for supporting a tub, said rails having at their rear ends links connecting them 15 with a fixed point below the top of the table, supplementing rail extensions hingedly connected with the forward ends of said first named rails and fulcrumed to fixed points to raise and lower the first named 20 rails.

5. In combination with a table, a pair of rails for supporting a tub, said rails having at their rear ends links connecting them

with fixed points below the top of the table, supplementing rail extensions hingedly connected with the forward ends of said rails and fulcrumed to fixed points, and legs supporting the free ends of said supplementing rail extensions.

6. In combination with a table, a pair of rails for supporting a tub, said rails having at their rear ends links connecting them with a fixed point below the top of the table, rail extensions hingedly connected with the forward ends of said rails and fulcrumed to a fixed point, legs supporting the free ends of said rail extensions and stops to confine the tub to said rails.

7. In combination with a table, rails for supporting a tub below the top of the table, 40 movable supplementing rail extensions for the first mentioned rails, said supplementing rail extensions operable to raise the first mentioned rails.

ALFRED CASTANIEN.
